SAMUEL MASON, OF NEWARK, NEW JERSEY.

Letters Patent No. 84,294, dated November 24, 1868.

IMPROVEMENT IN HORSE-SHOES.

The Schedule referred to in these Letters Patent and making part of the same.

To all whom it may concern:

Be it known that I, SAMUEL MASON, of the city of Newark, in the county of Essex, and State of New Jersey, have made certain Improvements in the Manufacture of Horse-Shoes; and I do hereby declare the following to be a full and exact description of the same, reference being had herein to the drawings that accompany this specification, as part of the same.

The nature of my improvement consists in a way of holding a calk to a shoe.

In the drawings—

Figure 1 is the shoe, with the calks attached, and Figure 2, various calks.

Upon the calks, as shown by *b*, there is, on one side, a small rib, and upon the other side an indentation, *c*, and upon the sides of the sockets that are cast as part of the shoe, there are corresponding ribs and indenta-

tions, as seen in fig. 1, and in an end view of the socket, at the bottom, fig. 2.

Through the sides of the socket a hole is bored across at the bottom, and in each calk is a corresponding groove, *e*. The pin *d*, passing through, holds the calk in its place, keeping it from slipping out. A slight incline in the bottom of the socket presses the ribs against the grooves when the calk is forced in.

What I claim as an improvement, and desire to secure, is—

The rib *b*, indentation *c*, the pin *d*, and the corresponding groove *e*, when combined in the manner and for the purpose specified.

SAMUEL MASON.
